UNITED STATES PATENT OFFICE.

MARVIN A. BETZER, OF SEATTLE, WASHINGTON.

DRIER.

1,247,495.

Specification of Letters Patent. Patented Nov. 20, 1917.

Application filed October 6, 1916. Serial No. 124,172.

To all whom it may concern:

Be it known that I, MARVIN A. BETZER, a citizen of the United States, residing at Seattle, in the county of King and State of Washington, have invented new and useful Improvements in Driers, of which the following is a specification.

This invention relates to driers especially designed for laundry use.

10 The object of the invention is to provide means for drying bathing suits or other apparel by subjecting them to artificial heat within a room or casing.

15 A further object of the invention is to provide means for supplying fresh air to the casing and evenly distributing it over the clothes in order to insure an even drying.

20 With the above objects in view the invention consists of a room or casing having heating coils arranged therein, clothes racks 25 slidable within said casing and between the heating coils, a fan for supplying air to a coil box, heating coils within said box for heating the air to be supplied to the casing and a fan for distributing the heated air evenly over the apparel.

In the drawings

Figure 1 is a front elevation of the invention;

30 Fig. 2 is a plan view of the same;

Fig. 3 is a longitudinal sectional view illustrating the racks partly extended; and

Fig. 4 is a cross sectional view showing the racks in position within the room.

35 Referring more specifically to the drawings, the numeral 1 indicates a room or casing, preferably of rectangular shape. Arranged within this casing and spaced apart are a number of main heating coils 2. These

40 coils are, as shown, preferably three in number and are designed to be supplied from a suitable source the heat through the pipe 3. Openings 4 are formed in the front of the room or casing for the reception of suitable

45 racks 5 to provide means for hanging the clothes.

The racks 5 comprise end members 6 connected together by longitudinal rods 7 arranged in tiers. Hangers 8 carrying grooved rollers 9 support the rack by means of guide rods 10. These rods are supported within the room and are so arranged that the clothes rack may be moved into or out of

the room to facilitate the handling of the clothes. One of the rollers 9 is arranged 55 within the room and acts as a stop to limit the movement of the rack in both directions.

As will be seen from the drawings, the ends 6 of the rack provide for the closing of the openings 4 when the rack is either 60 upon the outside or inside of the casing, so as to insure the retention of the heat within.

A fan 11 preferably supported from the top of the casing is adapted to supply air to a coil box 12, through the medium of the 65 flue 13. Arranged within the coil box is a steam or hot water coil 14 for the purpose of heating air supplied to the said box before entering the casing 1, by means of the pipes 15 leading from the coil box and into the 70 casing. Arranged between the pipes 15 and within the casing is a fan 16, the purpose of this fan being to spread or distribute the air over the racks in order to insure an even 75 drying of the clothes.

The purpose of supplying the room with fresh air heated before entering is to maintain the said room at an even temperature.

It is of course well known that air will only take up a certain amount of moisture 80 and in order to provide for the rapid drying of the clothes the freshly heated air is supplied.

A fan 16 may be driven from any suitable 85 source of power, the means shown consisting of pulleys 17 and 18 and a belt 19. The pulley 18 is fast to the power shaft 20, which may receive its power from any source.

A suitable outlet 21 may be provided in 90 the rear of the room 1 to permit the escape of the damp or dead air.

From the foregoing it will be seen that the invention provides a simple and economical means for drying clothes, by which 95 the greatest quantity of clothes may be dried within a minimum space.

Having thus described my invention, I claim:

1. A drying room comprising a casing, 100 heating coils within said casing, means for supplying heated fresh air to the interior of said casing, and active means located within the casing for distributing said heated air evenly within said casing.

2. A drying room comprising a casing, a 105

flue for supplying fresh air thereto, a heating coil located in said flue, a fan located at the entrance of said flue for forcing air around said coil and through the flue, an 5 agitator element located within said casing adjacent the opposite end of the flue for distributing the heated air evenly within the casing.

3. The combination with a drying room 10 comprising a casing having a series of spaced heating coils arranged therein, of drying racks mounted for sliding movement between said coils, said racks including end sections and longitudinal connecting bars

and means slidingly supporting said racks 15 for movement between said coils.

4. The combination with a drying room comprising a casing having a series of spaced heating coils arranged therein, drying racks mounted for sliding movement between said coils, said racks including end sections and longitudinal connecting bars, and longitudinally arranged supporting bars carried by said casing for slidingly supporting said racks for movement be- 20 tween said coils. 25

MARVIN A. BETZER.
